(57) **CLAIM**

The ornamental design for a tube clamp for prosthesis, as shown and described.

DESCRIPTION

FIG. 1 is a perspective view of a tube clamp for prosthesis in accordance with my new design;

FIG. 2 is another perspective view thereof;

FIG. 3 is a first side view thereof, which is identical to the opposite side view thereof, the front view thereof, and the back view thereof;

FIG. 4 is a top view thereof; and,

FIG. 5 is a bottom view thereof.

Any broken lines in the accompanying drawings represent portions of the tube clamp for prosthesis that form no part of the claimed design.
